(57) **CLAIM**

The ornamental design for an article for use in a display assembly, as shown and described.

DESCRIPTION

FIG. 1 is a front elevation of an article showing my new design in an assembled condition.

FIG. 2 is a reduced scale front perspective view thereof in the assembled condition.

FIG. 3 is a front perspective view thereof in a disassembled condition; and,

FIG. 4 is a reduced scale front elevation thereof and environmental structure.

The broken lines showing the intended environment of the design are for illustrative purposes only and form no part of the claimed design.
